CLAIM

I claim the ornamental design for an imitation emergency flare, as shown and described.

DESCRIPTION

FIG. 1 is a front view of the imitation emergency flare.
FIG. 2 is a left side view of the claimed design.
FIG. 3 is a right side view of the claimed design.
FIG. 4 is a top view of the claimed design.
FIG. 5 is a bottom view of the claimed design; and,
FIG. 6 is a perspective view of the claimed design.
The broken lines appearing on FIG. 2 is of an off/on switch
and is environmental matter forming no part of the claimed
design.
